A. O. Merkel
his Attorney

UNITED STATES PATENT OFFICE.

GEORGE E. KARL, OF BEREAL, OHIO, ASSIGNOR TO THE DUNHAM COMPANY, OF BEREAL,
OHIO, A CORPORATION OF OHIO.

LAND-ROLLER.

1,250,591.

Specification of Letters Patent. Patented Dec. 18, 1917.

Original application filed August 20, 1915, Serial No. 46,484. Divided and this application filed May 12, 1916. Serial No. 97,159.

To all whom it may concern:

Be it known that I, GEORGE E. KARL, a citizen of the United States, resident of Berea, county of Cuyahoga, and State of Ohio, have invented a new and useful Improvement in Land-Rollers, of which the following is a specification, the principle of the invention being herein explained and the best mode in which I have contemplated applying that principle, so as to distinguish it from other inventions.

My invention relates to land rollers and particularly to that class of rollers which are known as water ballast rollers in which water or sand is used as ballast, the subject-matter constituting a division of original application Serial No. 46,484, filed by me August 20, 1915.

The object of the invention is to provide a ballast roller construction which will be economical of manufacture and efficient in performance of its functions.

The said invention consists of means hereinafter fully described and particularly set forth in the claims.

The annexed drawing and the following description set forth in detail certain means embodying my invention, the disclosed means, however, constituting but one of various mechanical forms in which the principle of the invention may be applied.

In said annexed drawings:—

Figure 1 represents an axial section, with the handle omitted, of a land roller embodying my invention and showing the parts thereof occupying the position assumed prior to the complete assembling thereof.

Fig. 2 represents a section similar to that illustrated in Fig. 1, showing the parts in their final or assembled position and also showing fragmentary portions of the handle in section.

Fig. 3 represents upon an enlarged scale an axial section of the fragmentary portion of the device, one end of the axial shaft being shown in elevation. Fig. 4 is a modification.

The illustrated embodiment of my invention comprises an outer shell 1 of sheet metal bent into cylindrical form and having its meeting ends welded in the usual manner.

Inset into each end of such shell is a head 2 consisting of a main circular portion and

a peripheral flange 3. These heads are inset 55 a distance such that the end portions of the shell 1 originally extended beyond the outer extremities of the flanges whereby such shell end portions may be bent around and against the inner surfaces of the flanges, as 60 shown in Figs. 1 and 2. Such bending operation is performed by the use of well-known bending apparatus and the overlapping parts are pinched tightly together to form a water-tight joint. After these two 65 joints are formed as above described, or prior to the formation thereof, as may be found most expedient, each shell flange is integrally united at points intersected by a plane perpendicular to the shell's axis and 70 located at points 4 intermediate of the extreme inner ends 5 of the bent portion of the shell and the inner extremity 6 of the corresponding flange. This integral union is preferably performed by spot welding 75 and by means of suitable apparatus for this purpose well-known to those skilled in the art. The joint formed by the shell and flanges forms the subject-matter of my said original pending application and is separately claimed therein.

The central portion of each head is formed with a circular opening 7 through which openings extend the extremities of an axial shaft 8. These extremities are reduced 85 to form two shoulders 9 and 10, Fig. 3, the shoulder 9 being located interiorly of the drum and the shoulder 10 exteriorly thereof. The extreme end-portion 11 is cylindrical and forms a journal upon which the 90 roller bearings 12 of the handle 13 revolve. These bearings are held in place by means of a suitable washer 14 itself secured in place by means of a cotter pin 15. The inner ends 95 of the rollers are adjacent to the shoulder 10.

That portion of the end part of each shaft intermediate of the shoulders 9 and 10 is provided with a thread 16 which is engaged upon the outside of the head by a nut 17. Adjacent to the shoulder 9 is a 100 separating washer 18 and between this washer and the head is located a packing ring 19.

The distance between the two shoulders 9, 9, of the shaft is made less than the distance between the central portion of the heads 2 when the latter are in a normal position prior to the assembling of the parts,

as shown in Fig. 1, that is when the heads are in a state of internal rest.

The parts are completely assembled by screwing up the nuts 17 against the outside so as to cause the washers 18 to engage the shoulders 9, also to compress the packing ring 19 so as to effect a water-tight joint and also flex the heads inwardly, as shown in Fig. 2, and thus set up a condition of tension therein.

As a result of imparting to these heads the described tension, it will be seen that they are rendered very rigid and are, during the operation of the roller, prevented from flexing in the direction of the roller's axis.

Where this condition of tension is not set up in the heads, such flexing takes place during the operation of the roller and produces not only an undesirable noise, but also imparts an impression of looseness and weakness to the structure. This flexing is especially apparent in the case of water ballast rollers and where the interior is not completely filled with water and where, therefore, the latter is permitted to move laterally against these heads. This flexing movement furthermore tends to weaken the metal of the joints effected between it and the shell.

In the above-described manner, therefore, I obtain a very simple and rigid construction without unduly increasing the thickness of the heads.

While I have shown heads which are in a dished or bent form before assembling the parts, it will be understood that they may be originally perfectly flat, as shown in dotted lines in the drawing, as indicated in Fig. 2 assuming a dished form after assembly, the shaft 8 being suitably designed to meet these conditions, especially in so far as relates to the position of the shoulders 9.

It will also be obvious to those skilled in the art, that the above-described principle of construction may be applied to a land roller in which the heads, after the parts are all assembled and secured to each other, will be curved in the direction opposite from that shown in the drawings, that is, whereas the drawings show concave heads, convex heads may be formed if desired, either before or after assembling as indicated in Fig. 4.

Having fully described my invention, what I claim and desire to secure by Letters Patent is:—

1. In a land roller, the combination of a cylindrical shell; two end-heads secured in

the ends respectively of said shell; a shaft extending through said heads; and means for securing such shaft to the heads; said securing means being arranged to draw and flex the heads and create therein a condition of tension directed against the inner ends of the shell.

2. In a land roller, the combination of a cylindrical shell; two end heads secured in the ends respectively of said shell; a shaft extending through said heads and having its ends threaded and reduced so as to form two shoulders located interiorly of the heads and adjacent thereto; separating and packing means intermediate of said shoulders and heads, and nuts on said threaded ends of the shaft and on the exterior of said heads respectively, engaging the latter and clamping same against said separating and packing means; the said shoulders being located a distance from said heads such that said nuts set up a condition of tension in the heads when the parts are clamped together by said nuts.

3. In a land roller, the combination of a cylindrical shell; two end heads secured in the ends respectively of said shell; a shaft extending through said heads and having its ends threaded and reduced so as to form two shoulders located interiorly of the heads and adjacent thereto; separating and packing means intermediate of said shoulders and heads, and nuts on said threaded ends of the shaft and on the exterior of said heads respectively, engaging the latter and clamping same against said separating and packing means.

4. In a land roller, the combination of a smooth cylindrical metallic shell, provided with inturned ends, flanged heads engaging said inturned ends, said heads being provided each with a perforation, a shaft passing through said perforation, and means upon the shaft to apply force to said heads to tend to flex them, whereby the tension of flexure is made effective against the ends of the shell.

5. In a land roller, the combination of a smooth cylindrical metallic shell, provided with inturned ends, flanged heads engaging said ends, said flanges being also welded to the shell, said heads being provided each with a perforation, a shaft passing through said perforation, and means upon the shaft to apply force to said heads to tend to flex them, whereby the tension of flexure is made effective against the ends of the shell.

Signed by me, this 24th day of February, 1916.

GEORGE E. KARL.
